UNITED STATES PATENT OFFICE.

ERNEST I. BASS, OF CORNERSVILLE, TENNESSEE.

SPARK-PLUG TESTER.

1,333,698.

Specification of Letters Patent. Patented Mar. 16, 1920.

Application filed March 3, 1919. Serial No. 280,195.

To all whom it may concern:

Be it known that I, ERNEST I. BASS, a citizen of the United States, residing at Cornersville, in the county of Marshall and State of Tennessee, have invented a new and useful Spark-Plug Tester, of which the following is a specification.

This invention relates to improvements in spark plug testers, the object of the invention being to provide a tool which is primarily intended for use as a means for detecting the amount of spark being produced in the plug without the necessity of removing the plug from the cylinder head or any of its connections.

A further object of the invention is to provide a tool of the character set forth, and which may also be used as a pair of pliers, a wrench or a screwdriver.

20 A further object of the invention is to provide a combined tool of the character set forth which is comparatively simple in construction, inexpensive to manufacture and very reliable in its action.

25 With these and other objects in view, which will appear as the description proceeds, the invention consists in the novel features of construction and combination of parts, all of which will be more fully described hereinafter and finally pointed out in the claims.

In the drawings accompanying and forming part of this specification,

30 Figure 1 is a side view, partly in section, showing a combined tool constructed in accordance with my invention; and

Fig. 2 is an enlarged, cross-sectional view taken approximately on the line 2-2 of Fig. 1.

40 The same characters of reference designate the same parts in the figures of the drawings.

In the embodiment of the invention herein illustrated, 2 designates generally a pair of pliers having the usual double pivot hole through which passes a rivet 3, whereby the distance between the jaws of the pliers may be changed in order to permit the jaws to grip pipes or nuts of larger or smaller diameters, the jaws being provided with the usual serrated recesses 4 which coöperate to form a wrench for gripping such pipes or nuts.

In the present instance one of the shanks of the pliers is cut away at its outer side so as to form an abutment 5 and a supporting

portion 6 on which is secured, by means of screws 7 and 8 and a rivet 9, a member 10 of non-conducting material, such as fiber, hard rubber or similar material, as shown in Fig. 1. The member 10 is provided approximately at the center thereof with an opening 11 passing entirely therethrough and of suitable diameter for the purpose presently to be described. On the outer longitudinal edge of the member 10 is secured a plate 12 of brass or other suitable material, said plate be secured to the member 10 by means of a screw 13 and a pair of lugs 14, one at each end of the plate, which lugs may be stamped from the material of the plate and pressed down into the member 10. The ends of the screws 8 and 13 extend through the member 10 and into the opening 11 to approximately the same distance from each other as the electrodes of a spark plug, which is usually about $\frac{1}{2}$ of an inch, and this distance may be adjusted by tightening or loosening the screws 8 and 13. The other shank of the pliers is provided with an insulating cover 15 for preventing shock to the user in using the device in the manner hereinafter described. For increasing the usefulness of the tool, the free end of this shank is made in the form of a screwdriver, and is of approximately the same thickness as the distance between the electrodes of a spark plug, so that it may be used as a gage for correcting any displacement of such electrodes.

In the use of the tool as a spark plug tester, the screws 8 and 13 are adjusted so that their ends are at the proper distance apart. The tool is then taken hold of by grasping the shank having the insulating cover 15, and the butt end 16 placed on some conveniently located metal part of the engine while the plate 12 is placed in contact with the spark plug. If there is any current or spark passing through the plug it will be shown at the points of the screws 8 and 13. It will thus be seen that I have provided a handy tool by means of which if there is trouble with the engine and it is desired to ascertain whether the fault is in the spark plug this can be done in a few seconds and without the necessity of having to remove the plug or any of its connections.

While I have described in detail the structure illustrated, I do not desire to limit

my invention to the precise features of construction herein shown, as I am aware that many mechanical changes may be made therein without departing from the spirit 5 and scope of the invention as set forth in the appended claim.

Having thus described my invention, what I claim is:

In a spark plug tester, pivoted conduct-
10 ing members, one of the pivoted members
having an abutment, a block of non-conduct-
ing material supported by one of the pivoted
members, and engaging the abutment, said
block of non-conducting material having an
15 opening formed therethrough, a relatively
long metallic plate supported on the block,
of non-conducting material, screw members

extending into the block of non-conducting
material, one of the screw members having
connection with the metallic plate, the op- 20
posite screw member having connection
with one of the pivoted members, the ends
of the screw members lying in close prox-
imity with each other within the opening
to provide a spark gap, and an insulating 25
cover for the opposite pivoted member.

In testimony that I claim the foregoing
as my own I have hereto affixed my signa-
ture in the presence of two witnesses.

ERNEST I. BASS.
